DESIGN FOR A BOTTLE CRATE

Everett Worthington, Chicago, Ill., assignor to Coca-Cola Company, Atlanta, Ga., a corporation of Delaware

Application August 31, 1935, Serial No. 58,396

Term of patent 14 years

To all whom it may concern:

Be it known that I, Everett Worthington, residing at Chicago, in the county of Cook and State of Illinois, have invented a new, original, and ornamental Design for a Bottle Crate, of which the following is a specification, reference being had to the accompanying drawing, forming part thereof.

Figure 1 is a perspective view of my new bottle
crate;

Fig. 2 is a front elevation thereof; and
Fig. 3 is a side elevation.

I claim:

The ornamental design for a bottle crate, as shown.

EVERETT WORTHINGTON.
